UNITED STATES PATENT OFFICE.

ALBERT P. BRAYTON, JR., OF SAN FRANCISCO, CALIFORNIA.

DESIGN FOR A WATER-WHEEL CASING.

SPECIFICATION forming part of Design No. 21,286, dated January 5, 1892.

Application filed May 14, 1891. Serial No. 392,778. Term of patent 14 years.

To all whom it may concern:

Be it known that I, ALBERT P. BRAYTON, Jr., a citizen of the United States, residing at San Francisco, county of San Francisco, and State of California, have invented certain new and useful Improvements in a Design for Water-Wheel Frames or Casings; and I hereby declare the following to be a full, clear, and exact description of the same, reference being had to the accompanying drawings, forming a part of this specification.

Figure 1 is a perspective view of a water-wheel casing shaped in accordance with my new design. Fig. 2 is a rear perspective view of the same viewed obliquely from the side.

My newly-designed water-wheel casing comprises the upper semicircularly-outlined part A', having a curved or rounded periphery, with a concentric semicircular depression A³ represented in the front thereof, the inner face of which depression is a flat vertical surface. Said part A' is shown as mounted upon a horizontal division edge or plate B. The rear side of the part A' is provided with a semicircular depression A⁴, similar to the depression A³ in the front side. (See Fig. 2.) Below the edge B is a curved part A², similar in

general shape to the upper part A', but not provided on its front side with a depression, said front side being partially straight and smooth, as shown at a. The rear side of the part A², as shown in Fig. 2, has a depression a', situated below the division-edge B. The lower part A² loses the definiteness of its semicircular form near the bottom, where it merges into a horizontal tangential enlargement or rounding tangential contour C and also into a vertical rounding outline D, located midway below the part A² and in conjunction with the enlargement C. Below the entire design, as just described, is a flat thin horizontal base E, whereon what is shown above is mounted.

What I claim is—

The design for a water-wheel frame or casing, substantially as herein described and shown.

In testimony whereof I have hereunto affixed my signature in the presence of two witnesses.

ALBERT P. BRAYTON, JR.
